UNITED STATES PATENT OFFICE.

THEODORE A. HUNTER, OF WASHINGTON, DISTRICT OF COLUMBIA.

ADVERTISING NOVELTY.

Application filed November 20, 1924. Serial No. 751,150.

To all whom it may concern:

Be it known that I, THEODORE A. HUNTER, a citizen of the United States, residing at Washington, in the District of Columbia, have invented new and useful Improvements in Advertising Novelties, of which the following is a specification.

This invention relates to advertising novelties. The object is to produce a simple 10 novelty which can be cheaply manufactured, and which will attract the eye, especially of persons who play golf. As it is the golfer's ideal to be able to make a hole in one shot, the representation of a golf ball 15 with a hole in it, and the phrase "a hole in one," immediately catches the eye of the person who plays golf. Any desired advertisement can be applied to the novelty or sent along with it, as desired.

Fig. 1 shows a front view; and

This invention comprises a base member 1 of wood or other suitable material, upon 25 which preferably an imitation of a half of a golf ball 2 is fastened by glue or any desired fastening means. The golf ball may be represented in any other desired way, however. Part 2 may be made of wood, rubber, papier mâché, or any other desired 30 material. In part 2 is provided a hole 3. The base 1 may also have a hole 4. Upon the base 1 the words "The golfer's dream—a hole in one" is preferably applied as indicated or in any other desired way. 35

The foregoing description taken in connection with the accompanying drawing is to be considered illustrative and not limiting.

I claim:

1. A device symbolizing a golf ball with a hole in it.
2. A base member containing thereon a device symbolizing a golf ball with a hole in it.
3. A base member containing thereon a device having the shape and appearance of a portion of a golf ball with a hole in it, and carrying symbols suggesting "A hole in one."

THEODORE A. HUNTER.
